CLAIM

The ornamental design for a scalpel handle, as shown and described.

DESCRIPTION

FIG. 1 is a top isometric view of a scalpel handle in accordance with the new design, a bottom isometric view being a mirror image thereof;

FIG. 2 is a left side elevation view thereof, a right side elevation view being a mirror image thereof;

FIG. 3 is a rear isometric view thereof; and,

FIG. 4 is a front isometric view thereof.

1 Claim, 4 Drawing Sheets

FIG. 3

FIG. 4
